GOVERNOR

Addison C. Hoof, Hinsdale, Ill.

Application September 17, 1932, Serial No. 633,695

8 Claims. (Cl. 137—152)

This invention relates to improvements in governors more particularly for gas engines, where a throttle valve is inserted in the neck of the intake manifold; and the closing movements thereof, under the forces created by the cylinder displacement at different loads for a desired speed are balanced by a spring resistance.

Objects of the invention are to provide a simple, practical form of governor which will automatically control the speed within close limits at different loads as on level stretches and going up grades; to provide a resistance which increases rapidly as the valve is nearing its closed position, in correspondence with the increase in the turning forces exerted on the valve near the closed position; and to provide an arrangement which can readily be set for different speeds, the arrangement being such that the said increase or building up in resistance is automatically greater for the higher speed settings and higher resistance tensions, than for lower speeds, in accordance with the differences in the turning forces at the different speeds for the same valve positions.

Further objects are to provide a governor having a key controlled adjustment, and a closure which is locked by the same key to prevent tampering.

Other objects and advantages will become apparent in the following description, of an illustration embodiment of the invention, with reference to the accompanying drawing, in which:

Fig. 1 is a side elevation, partly in section, of the governor incorporated in a block 10 which is inserted between the bolting flanges of the engine intake manifold and the carburetor, as will be understood.

Fig. 2 is a plan section, taken substantially on the line 2—2 of Fig. 3, with parts shown in full.

Fig. 4 is a partial section on the line 7—7 of Fig. 3.

Fig. 5 is a detail section taken on line 5—5 of Fig. 1.

On one side of the block 10 is formed a housing 11, having a chamber 12 which is covered by means of a removable plate 13. An intake duct section 14 extends vertically through the block, and in the block is journaled a horizontally disposed shaft 15 which extends through at one side of the duct and into the chamber 12. In the duct a plate valve 16 is rigidly secured to the shaft; and on the outer end of the shaft, within the housing, is pinned an arm 17—having a roller 18 rotatably mounted on its outer end. In the wide open position of the valve, the arm 17 abuts against

a stop lug 18a, formed on the adjacent wall of the housing.

In the base of the housing 11, below and at the side of the shaft opposite the arm 17, is formed a boss 19 in which is rotatably mounted a block 20 which has a lug 21 extending into the boss. The block 20 has a transverse slot 22 in which is clamped, by means of screw 24, a multiple graduated leaf spring 25 which extends below the shaft substantially parallel with the arm in the open position of the valve, the longest leaf being in co-operable relation with roller 18.

A screw 26 is rotatably mounted in a lug 27; formed on the lower wall of the housing, and threaded on the screw is nut 28 which is engaged in a notch 29 formed in the lower end of the block 20. Thus the spring 25 may be swung towards or away from the arm 17 by rotating the screw 26 to effect tension adjustments.

In the lower corner of the housing is provided a boss 30 which has a bore 31, in alignment with the screw 26, for receiving a lock cylinder 32, having transversely disposed locking tumblers 33. On the inner end of the cylinder is an eccentrically disposed lug 34 which enters a cross slot 35 milled in the head 36, of the screw 26, so that the rotative position of the screw is controlled by the lock cylinder.

The enlarged end 37 of the lock cylinder 32, abuts against a shoulder 38, formed in the bore 31, and oppositely disposed longitudinal slots 39 are formed in the walls of the bore for locking engagement of the tumblers 33.

The cover plate 13 is locked in position by the insertion of the cylinder 32. On the inner side of the upper edge of the plate 13 are provided two curved lugs 40 which hook into suitable slots 41 provided in the upper wall of the housing 11; and on the lower corner of the cover is a lug 42 which enters an enlarged recess 43 in the housing which is intercepted by the bore 31. The lug 42 is provided with an aperture 44 which registers with the cylinder bore 31 when the cover is in closed position, and receives the lock cylinder.

The cylinder is prevented from withdrawal by means of a radial lug 45 formed on the inner end thereof. The cylinder is inserted with the tumblers retracted and the lug 45 is passed through a notch 46, formed in one side of the aperture 44, which registers 90° from the tumbler slots 39; and, as the cylinder is rotated to locking position the lug 45 rotates in the recess 43 and engages behind the cover lug 42.

The cover 13 is provided with a lug 47 for holding the block 20 in position.

In operation, the flow of the gases through the intake duct 14 tends to rotate the valve 16 towards closing position, until the valve reaches a position at which the torque on the shaft, and opposing resistance of the spring are equal.

The resistance of the spring is built up and the stiffness of the spring increases at an ever increasing rate as the flexure is increased, and this building up of resistance is further accentuated 10 as the roller 18 rides up on the spring and moves closer to the support block 20. Thus by proportioning the various parts, and regulating the effective lengths of the leaves, the resistance can be regulated to closely approximate the torque 15 on the shaft at each position of the valve for the desired engine speed.

By changing the position of the block 20, rotatively, by turning the screw 26, the governed speed can be changed as desired, and the resistance is increased more rapidly at higher tensions, 20 in accordance with the greater increases in the torque at closed valve positions for higher speeds on account of the greater degree of flexure of the spring, so that good regulation can be obtained at different speeds.

Having thus described my invention, I claim:

1. A governor comprising a rotatably mounted shaft, a throttle valve and a crank arm fixedly secured to the shaft, a support and a leaf spring 30 mounted on the support slidably contacted by the outer end of the crank arm, the spring being disposed so that the contact of the arm approaches the support as the valve is moved toward closed position.

35 2. In combination with an unbalanced throttle valve, means for resisting the closing movement of the valve comprising a leaf spring, a rotatably mounted block for holding one end of the spring, the spring being clamped rigidly in the block and extending tangent to the axis of rotation and a screw for securing and adjusting the block in rotative position to regulate the tension of the spring.

3. In combination with a throttle valve, means 45 for resisting the closing movement of the valve comprising a rotatably mounted block, a leaf spring rigidly mounted on the block and projecting laterally therefrom for resisting the closing movement of the valve, a rotatably mounted 50 screw and a nut threaded on the screw and in engagement with the block so that the tension of the spring may be adjusted by rotating the screw.

4. A governor comprising a housing, a rotatable 55 shaft mounted therein, a throttle valve fixedly secured thereto at one end thereof, a crank arm secured thereto at the other end, a support pivotally mounted in said housing, a leaf spring assembly secured to said support and slidably 60 contacted by the outer end of said crank arm.

the spring assembly being disposed so that the contact of the arm approaches the support as the valve is moved toward a closed position.

5. A governor comprising a housing, a rotatable shaft mounted therein, a throttle valve fixedly secured thereto at one end thereof, a crank arm secured thereto at the other end, a roller fastened to the end of said crank arm, a support pivotally mounted in said housing, a leaf spring assembly secured to said support and slidably contacted by said roller, the spring assembly being disposed so that the contact of the arm approaches the support as the valve is moved toward a closed position.

6. A governor comprising a member formed 15 with a conduit portion and a housing portion, a rotatable shaft mounted in said member extending through said conduit adjacent one side thereof and into said housing portion, a flat valve plate secured thereto in said conduit, a crank arm secured to the end in said housing, a roller mounted on said arm, a support having a square opening therethrough pivotally mounted in said housing, and a plurality of leaf springs of different 20 lengths secured in said square opening and extending therefrom, said roller adapted to contact the longest of said leaf springs and upon rotary movement of said shaft bring all of said springs under stress.

7. A governor comprising a member formed 30 with a conduit portion and a housing portion, a rotatable shaft mounted in said member extending through said conduit adjacent one side thereof and into said housing portion, a flat valve plate secured thereto in said conduit, a crank arm secured to the end in said housing, a roller mounted on said arm, a support having a square opening therethrough pivotally mounted in said housing, and a plurality of leaf springs of different lengths secured in said square opening and extending 35 therefrom, said roller adapted to contact the longest of said leaf springs and upon rotary movement of said shaft bring all of said springs under stress, and means for adjusting said spring support to change the initial position of said leaf 45 springs.

8. In combination with an unbalanced throttle valve, means for resisting the closing movement of the valve, comprising a leaf spring, said spring 50 consisting of a plurality of leaves of graduated lengths, a rotatably mounted block for holding one end of the spring, the end of the leaf spring being rigidly clamped in the block so that the spring projects laterally from the block and tangent to the axis of rotation, and a screw for securing and adjusting the block back and forth in rotative position to regulate the tension of the 55 spring.

ADDISON C. HOOF. 60
